Attorney

UNITED STATES PATENT OFFICE.

NEWTON ABSOLUM SMITH, OF MARION, ILLINOIS, ASSIGNOR OF ONE-HALF TO
CLARENCE WOOD, OF CAMBRIA, ILLINOIS.

TANK.

Application filed October 28, 1921. Serial No. 511,207.

To all whom it may concern:

Be it known that I, NEWTON A. SMITH, a citizen of the United States, residing at Marion, in the county of Williamson and 5 State of Illinois, have invented a new and useful Tank, of which the following is a specification.

This invention relates to ore or coal washers, it being the primary object of the 10 invention to provide a washer of this type designed to float the coal or lighter substance to a place of deposit.

A further object of the invention is to provide an endless conveyor adapted to receive 15 the heavier substances for moving them to a place of deposit.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 20 within the scope of what is claimed, without departing from the spirit of the invention.

Referring to the drawing:—

Figure 1 is a longitudinal sectional view 25 through a washer constructed in accordance with the present invention.

Figure 2 is a sectional view taken on line 2—2 of Figure 1.

Referring to the drawings in detail, the reference character 5 designates the body 30 portion of the washer, which is in the form of a relatively long tank having an offset portion 6 in communication therewith providing a housing for the lower portion of the conveyor 7 which operates over pulleys 35 provided at the upper ends of the standards 8, the conveyor 7 operating at an angle with respect to the main tank 5, the buckets 9 carried thereby operating to discharge material from the buckets into a wagon or similar vehicle which may be positioned adjacent to the standards 8.

Shafts 10 are disposed at each end of the body portion or main tank 5, on which shafts are supported the rollers 11 over 50 which operate the endless belt 12 that carries the transverse bars 13 which feed the material towards one end of the body portion.

The bars 13 constitute the traveling baf-

fles which cooperate with the stationary baffles 14 that are secured to the side walls of 55 the body portion 5 in any suitable manner, and disposed at angles with respect thereto, so that material fed onto the endless belt 12 will be agitated under the operation of the traveling baffles. 60

A supply tank 15 is supported adjacent to one end of the body portion 5 and supplies water to the body portion or tank through the supply pipe 16, the flow of water to the tank being controlled by the 65 valve 17.

Material is fed to the washer through the chute 18, which in turn is supplied with the material to be washed from any suitable source. Operating at one end of the 70 body portion 5 is an endless conveyor 19 that has one end thereof disposed in the body portion 5 adjacent to the endless belt 12, where material which floats upwardly above the stationary baffles 14 may be deposited in the buckets 20 of the endless conveyor 19. 75

From the foregoing it will be seen that as coal or similar material is fed to the body portion 5 and the movable baffles operated, the material is agitated, the lighter substances such as coal or the like, passing upwardly towards the upper portion of the body 5, where the same is delivered to the buckets. 80

It is to be understood however that the body portion 5 or tank, is supplied with water until the same reach a predetermined level in the body portion or tank 5, whereupon the machine may be operated to 90 accomplish the washing result. It might be further stated that the endless conveyors forming parts of the device may be operated in any suitable manner.

Having thus described the invention what 95 is claimed as new is:—

In a device of the character described, a tank having a fluid supply means, means to feed material thereto, a plurality of inclined stationary baffles positioned between 100 the side walls of the tank, an endless belt operating in the tank and adapted to receive material from the feeding means, transverse bars on the belt, said bars operating in proximity to the lower edges of 105 the stationary baffles, said belt adapted to

convey material to the discharge end of the tank, a laterally operated endless conveyor adapted to receive material from the tank, and a conveyor operating at one end of the tank to receive material directly from the endless belt.

In testimony that I claim the foregoing

as my own, I have hereto affixed my signature in the presence of two witnesses.

NEWTON ABSOLUM SMITH.
